KNOCK-DOWN PARTITION ASSEMBLY

Elmer Edward Koenig, Garfield Heights, Ohio,
assignor to The Mills Company, Cleveland,
Ohio, a corporation of Ohio

Application February 8, 1932, Serial No. 591,671

15 Claims. (Cl. 189—34)

This invention relates to a knock-down partition assembly and more particularly to a novel cornice and post construction, including means for adjusting, connecting and disconnecting 5 same.

In partition units heretofore constructed, great difficulty has been encountered in obtaining requisite strength along the cornice, especially where no bracing is provided from the ceiling. 10 Sturdy means for connecting the cornice to the partition wall units must also be provided so that the partition as a whole will be adequately braced and strengthened. Where the partition is of the knock-down type, the difficulty of obtaining the 15 requisite strength is greatly increased.

An object of my invention is to provide a knock-down partition assembly which is inexpensive to manufacture and erect and is unusually strong and sturdy.

Another object of my invention is to provide 20 a knock-down partition assembly having adjustable means for firmly securing the cornice to the partition post and partition wall unit.

A further object of my invention is to provide 25 a knock-down partition unit constructed so as to facilitate wiring within and through the partition post and cornice.

Another object of my invention is to provide 30 a sturdy cornice construction which is extremely flexible, which can be run any length without the use of welded braces, straps or splices and which will permit a wide range of artistic designs without sacrifice to the strength-giving features of the construction.

Other objects of this invention will become 35 apparent as the disclosure proceeds.

Although the novel features which are believed 40 to be characteristic of this invention will be particularly pointed out in the claims appended hereto, the invention itself, as to its objects and advantages, and the manner in which it may be carried out, may be better understood by referring to the following description taken in connection with the accompanying drawing forming 45 a part thereof, in which:

Fig. 1 is a vertical end view of the cornice member and a portion of the partition wall unit, this view being taken on the line 1—1 of Fig. 3;

Fig. 2 is a horizontal cross-sectional view 50 through the cornice member, the partition post supporting the cornice member being shown in dotted lines, this view being taken on line 2—2 of Fig. 1;

Fig. 3 is a vertical face view of the partition 55 assembly, parts being broken away to more clearly

show certain features of the construction; and

Fig. 4 is a vertical cross-sectional view through the cornice member and partition post, showing more particularly the means for rigidly and adjustably securing the same together, this view 5 being taken on line 4—4 of Fig. 3.

Like reference characters denote like parts in the several figures of the drawing.

I have shown in the drawing a knock-down partition assembly having a cornice unit 10 which 10 rests upon spaced uprights 11 and 12. My cornice unit is provided with an inner channel-shaped member which gives rugged strength to the cornice unit and an outer trim member which may be so shaped as to provide a pleasing and 15 artistic appearance. The outer trim member is generally channel-shaped in cross section, the side walls 13 thereof being formed into any suitable artistic design. The web portion 14 of the channel seats against the uprights 11 and 12. 20 The web portion 14 is recessed, as shown in Fig. 1, to receive the frame member 36 of the partition panel 50. The partition panel 50 may be of sheet metal, glass, wood, fibre, or composition material and made either solid, hollow or laminated. 25 This recess is formed by stamping the web portion 14 inwardly defining side wall portions 15 and bottom portion 16. The top edge of the side walls 13 of the trim member may be bent to provide inwardly extending flanges 17, which greatly 30 strengthens the trim member and cornice unit as a whole.

Within the trim member is securely seated a channel shaped strengthening member which may be of such gauge as is necessary for rigid strength. 35 This channel shaped strengthening member is provided with side walls 18 which snugly seat against the inner faces of the side walls 13 of the trim member. The web portion 19 of the strengthening member is recessed as at 20, this 40 recess 20 being adapted to receive certain parts of a filler or superstructure unit (not shown) which extends from the cornice to the ceiling. The strengthening channel member is preferably inverted, as shown in Fig. 1, and the side walls 18 45 thereof are provided with inwardly extending flange portions 21 which seat closely against the inner face of the web portions 14 of the trim member. The flange portions 21 are also provided with upwardly turned edge portions 22 50 which seat against and extend slightly above the side wall portions 15 of the trim member.

The vertical uprights 11 and 12 are generally spaced apart and preferably channel-shaped in general outline. Each upright comprises side face 55

portions 23 formed into any desired artistic design and the web portion 24 which is recessed as at 25 to receive the edge of the wall panel 50. The side walls 23 are provided with inwardly turned flange portions 26 which give added strength to the upright and also provide means with which upright connecting means, of which clip member 28 forms a part, may engage to bind the uprights firmly together in spaced relationship.

The means for securing the cornice unit and assembled partition posts, comprising uprights 11 and 12, rigidly and adjustably together, will now be described. A U-shaped yoke member 29 is provided with hook portions 30 which seat over and engage edge portions 22 of the inner strengthening channel member. The yoke member extends down through an aperture 31 provided in the bottom portion 16 of the trim member. A long adjusting screw 31a is threaded through the saddle portion 32 of the yoke member. The threaded screw 31 carries a sturdy bridge or bar member 33 which rests upon the head of the screw. A strap member 34 is suitably riveted as at 35, welded or otherwise secured to the side walls 23 of each of the uprights 11 and 12. The bridge member 33 is so arranged that each end thereof seats under and engages one of the strap members 34 provided on the uprights 11 and 12 respectively.

It is now seen that by manipulating the adjusting screw 31, the cornice unit may be pulled tightly into seating position on the uprights 11 and 12 at the same time and the entire cornice and post unit thus clamped and drawn together in a firm and immovable manner. The grip of the yoke member can be released by a few turns of the screw bolt 31a and the entire assembly can be disconnected and taken apart. To facilitate assembly and disassembly, the aperture 31 is of such size and shape as to permit the hook portions 30 of the yoke member 29 to slip through when moved in a position parallel with the cornice run. The apertures 31 may be cut into the bottom of the trim member at spaced intervals of say 6 inches so that the same cornice unit may be used for partitions having panel units of different widths. The uprights 11 and 12 can then be positioned at the points desired along the cornice run to accommodate the various panel unit widths. The longitudinal aperture 31 in the cornice unit is so shaped as to permit the passage of wiring conduits and cables therethrough at any time after the partition is erected.

The upper edge of the wall panel 50 is held in place by means of a panel frame or moulding 36 which seats within the recess 16 provided in the trim member. The panel frame 36 is formed as shown more particularly in Fig. 1 and has an abutment portion 38 against which the wall panel 50 abuts. The wall panel 50 is locked in place by means of a trim strip having an abutment portion 39 similar to the abutment portion 38 of the frame 36. Moulding strip 39 is provided with a long leg portion 41 which seats within a recess portion 42, formed by a sharp rebend in the frame member 36. When the panel 50 is to be inserted or removed, the moulding strip 39 can be easily removed by withdrawing the same out of engagement with the recess portion 41. To give the panel frame 38 additional strength a channel piece 43 may be provided which binds together and stiffens the leg portions 44 thereof.

It is now seen that when the wall panel 50, panel frame 36, uprights 10 and 11 and the cor-

nice unit are assembled as above described, lateral shifting of the cornice unit with respect to the partition post is positively prevented. The inner stiffening channel of the cornice unit fits snugly within the trim member and the joints of one are staggered with respect to the other so that these members comprising the cornice unit act to reinforce each other and eliminate the necessity of splicing, welding or bolting at the joints. My cornice unit is free from welds, rivets or bolts and thus is free from blemish and can be made more economically. Furthermore, my cornice unit construction permits great flexibility of artistic design since the exposed face portions 13 of the trim member may be formed into any number of artistic designs without affecting the strength of the cornice unit or requiring any change in the general structural features above outlined. The inverted strengthening channel member also forms an enclosed and protective housing for electric wiring, conduits and pipes, and these wires, conduits and pipes can be threaded through the apertures 31 into the panel posts without difficulty.

The cornice unit and wall units may be rapidly assembled and disassembled by a slight manipulation of the screw bolt 31. This feature of quick and positive adjustability is of great advantage where a partition of knockdown type is desired.

While certain novel features of the invention 30 have been disclosed and are pointed out in the annexed claims, it will be understood that various omissions, substitutions and changes may be made by those skilled in the art without departing from the spirit of the invention. 35

What is claimed is:

1. A partition assembly including hollow vertical and horizontal members, and adjustable take-up means concealed within said hollow members and adjustably connecting the same, 40 said take-up means comprising a yoke having spaced arms connected to one of said members, and an adjustable screw connecting said yoke and another of said members.

2. A partition assembly including hollow vertical and horizontal members, and adjustable take-up means concealed within said hollow members and adjustably connecting the same, 45 said take-up means comprising a yoke having spaced hooks connected to one of said members, a bridge member connected to another of said members, and adjustable means connecting said yoke and bridge member.

3. A partition assembly including hollow vertical and horizontal members, and adjustable 55 take-up means concealed within said hollow members and adjustably connecting the same, said take-up means comprising a yoke having a pair of spaced hooks releasably connected to one of said members, a bridge member connected 60 to another of said members, and an adjustable screw connecting said yoke and bridge member.

4. A partition assembly including hollow vertical and horizontal members, and adjustable take-up means concealed within said hollow 65 members and adjustably connecting the same, said take-up means comprising a yoke having a pair of spaced hooks releasably connected to one of said members, a pair of strap members connected to another of said members, a bridge 70 member extending between said strap members, and an adjustable screw connecting said yoke and bridge member.

5. A partition assembly of the character described including a hollow post, a cornice mem- 75

ber seated on said post, and take-up means adjustably connecting said post and cornice member comprising a hook element releasably engaging the cornice member and extending into the post, and adjustable means connecting said hook element to said post.

6. A partition assembly of the character described including a hollow post, a cornice member seated on said post, and take-up means adjustably connecting said post and cornice member comprising a hook element releasably engaging the cornice member and extending into the post, a bridge member mounted within said hollow post, and adjustable means connecting said hook element and bridge member.

7. A partition assembly of the character described including a hollow post, a cornice member seated on said post, and take-up means adjustably connecting said post and cornice member; said take-up means including a yoke having a pair of hook portions engaging the cornice member and extending into the post, a bridge member mounted within said hollow post, and adjustable means connecting said yoke and bridge member.

8. A partition assembly of the character described including a hollow post, a cornice member seated on said post, and take-up means adjustably connecting said post and cornice member, said take-up means including a yoke extending through an aperture in said cornice members and into the hollow post, said yoke having hook portions engaging the cornice member along the sides of said aperture, a bridge member mounted within the post, and an adjustable screw connecting said yoke and bridge member.

9. A partition assembly comprising spaced verticals, clips connected to said verticals to maintain the same in fixed spaced relationship, a channel shaped cornice member seated on said verticals, and adjustable take-up means connecting said spaced verticals and cornice member, said means including hook portions adapted to releasably engage said cornice member.

45 10. A partition assembly comprising spaced verticals, a bridge member extending between said verticals, a channel shaped cornice member seated on said verticals, a yoke having hook portions engaging said cornice member, and adjustable means connecting said yoke and bridge member.

50 11. A partition assembly of the character described including a post member and a cornice unit mounted on said post member, said cornice unit comprising a one piece outer channel shaped member having the flanges thereof upturned and formed into a decorative design, and a one piece inner strengthening channel member extending

substantially the full length of said outer member, said strengthening member having side flange portions seated against the inside face of the flanges of said outer member and extending substantially to the web portion thereof.

5 12. A partition assembly including vertical and horizontal members, and adjustable take-up means connecting said members, said take-up means comprising a yoke having spaced hooks connected to one of said members, and adjustable means connected to said yoke and another of said members.

13. A partition assembly of the character described including, a plurality of removable panel units, a cornice unit extending continuously over said panel units providing a lateral thrust resisting framework therefor, said cornice unit comprising an outer member of generally channel shape extending continuously over said panel units, said outer member having a web portion 20 and upturned flange portions, and a reinforcing channel seated within said outer member and extending substantially the full length thereof, said reinforcing channel having down-turned side wall portions seated against the inside face 25 of the flange portions of the outer member, and an inturned portion seated against the web portion of said outer member.

14. A partition assembly of the character described including, a plurality of removable panel 30 units, a cornice unit extending continuously over said panel units providing a lateral thrust resisting framework therefor, said cornice unit comprising an outer member of generally channel shape extending continuously over said panel 35 units, said outer member having a web portion and upturned flange portions, and a reinforcing channel seated in inverted position within said outer member and extending substantially the full length thereof, said reinforcing channel 40 having side wall portions seated against and closely conforming to the inside contour of the flange portions of the outer member and in-turned portions extending from said side wall portions seated against the web portion of the 45 outer member.

15. A partition assembly of the character described including a post member and a cornice unit mounted on said post member, said cornice unit comprising one-piece outer channel shaped 50 sections arranged in end to end abutment, each of said sections having the flange portions thereof upturned, and a one-piece inner reinforcing channel shaped member closely conforming to the inner contour of said outer channel shaped 55 sections extending across the abutting ends thereof.

ELMER EDWARD KOENIG.
